UNITED STATES PATENT OFFICE.

ARTHUR L. COLTON, OF CLEVELAND, OHIO.

FASTENER.

SPECIFICATION forming part of Letters Patent No. 398,819, dated March 5, 1889.

Application filed June 28, 1888. Serial No. 278,491. (No model.)

To all whom it may concern:

Be it known that I, ARTHUR L. COLTON, of Cleveland, in the county of Cuyahoga and State of Ohio, have invented certain new and useful Improvements in Fasteners; and I do hereby declare the following to be a full, clear, and exact description of the invention, such as will enable others skilled in the art to which it pertains to make and use the same.

10 My invention relates to improved fasteners for detachably securing elastic bands to, for instance, file-cases, memorandum-books, file-wrappers, and various other articles to which rubbers are applied for holding such articles closed.

15 My improved fastener consists in the main of a tongue, preferably flexible or elastic, said tongue being secured at the one end thereof to the cover, flap, or back, as the case may be, of the article, such tongue extending across a suitable hole made in such cover, flap, or back, with the free end of the tongue resting against the inner face of the article, book, file-wrapper, or whatever it may be. The 20 rubber band is slipped onto the free end of the tongue, and the band is then passed through the hole, leaving the band in the main on the outside of the article; but as the band remains astride the tongue it is securely, but 25 detachably, fastened to the article, to the end that the band is easily detached whenever it becomes broken or relaxed and a new band can be attached in its place.

30 In the accompanying drawings, Figures 1 and 2 are views in perspective showing my improved fasteners attached, respectively, to a memorandum-book and to a file-case. Fig. 3 is a plan showing the fastener attached to a wrapper. Figs. 4, 5, 6, and 7 are enlarged details hereinafter described.

35 A represents a tongue, usually of thin sheet metal, this tongue being fastened at the one end thereof to the cover, flap, or back of the article, as the case may be, such tongue extending across a hole, B, previously made in such cover, flap, or back of the article, with the free end of the tongue on the inside. The 40 rubber band C is slipped onto the free end of the tongue from the inside of the article, and the band is then thrust outward through hole 45 B, thus bringing the rubber band in the main on the outside of the article, but of course

leaving the band astride the tongue. By reversing the method the band is readily detached from the article. Sometimes one or 50 more slight rubber bands, c, (see Fig. 1,) are placed on the tongue by the side of the heavier band, C. Such small bands are convenient for holding a portion of the leaves, for instance, of a memorandum-book, so that the 55 latter will open at a given page, as required. If the material of the article to which the tongue is attached is of sufficient consistency, the tongue may be riveted or soldered on, according to the material to which it is attached. 60 For covers of light material—such, for instance, as paper, light leather, or card-board, &c.—a re-enforcing band, A', is fastened on the article around hole B, and the tongue A is preferably integral with such re-enforcing 65 band.

In Fig. 7 is shown a fastening device of this kind as it comes from the dies, the device being stamped from very thin sheet metal, preferably brass. The points a are turned down 70 at right angles to the body of the fastener, and these points are pressed through the cover, preferably from the outside, and clinched on the inside, the hole B having been previously made; also, in assembling the parts the free 75 end of the tongue is pressed inward and the material, d, of the cover or flap is passed between the tongue A and re-enforcing band A', as shown more clearly in Figs. 4 and 5, and the material, d, prevents the free end of the tongue 80 from drawing outward by the draft of the rubber band.

The file-case shown in Fig. 2 is supposed to have a metal back, D, and in Fig. 6 is shown a preferable manner of arranging the tongue 85 A, the latter being soldered onto the inside of member D, the tongue in this instance being offset outward at the middle portion thereof, so that the rubber band will not draw across the edges of the metal plate D.

90 My improved fastener is quite inexpensive, the initial cost thereof in quantities being only a small fraction of a cent each.

95 Rubber bands are considered much more convenient than tape for holding together file-cases, wrappers, memorandum-books, and various other articles. Heretofore the trouble has been in the use of rubber bands for such purpose that the bands were usually perma-

nently secured to the article, and when the band became broken or relaxed there was no convenient means provided for attaching a new band, and in case the band was not fastened to the article the band was usually lost. It will be seen that my improved fastener entirely overcomes this difficulty, and will be found very convenient for the purposes for which it is intended.

10 What I claim is—

1. A fastening for detachably securing an elastic band to book, file-case, wrapper, or other article, such fastening consisting substantially of an elastic tongue fastened to and extending across a hole in the cover, flap, or casing of such article, the free end of the tongue overlapping the inside of such cover, flap, or casing, or an attachment thereof, to prevent the tongue from bending outward through such holes, substantially as set forth.
2. In a fastening for an elastic band, the combination, with a suitable hole in the cover, flap, or casing, for instance, of a book, wrapper, or other article, and a tongue fastened to and extending across a hole in and the free end of the tongue overlapping on the inside of such cover, flap, or casing, of a re-enforcing band secured around such hole, such tongue and re-enforcing band being preferably integral, substantially as set forth.

In testimony whereof I sign this specification, in the presence of two witnesses, this 19th day of March, 1888.

ARTHUR L. COLTON.
